UNITED STATES PATENT OFFICE.

HARRY W. TUCKEY, OF SAN FRANCISCO, AND LUCIEN W. KLINE, OF ALAMEDA, CALIFORNIA.

DESIGN FOR A BADGE.

No. 37,720.

Specification for Design.

Patented Dec. 12, 1905.

Application filed July 17, 1905. Serial No. 270,141. Term of patent 14 years.

To all whom it may concern:

Be it known that we, HARRY W. TUCKEY, residing at 2042 Green street, in the city of San Francisco, county of San Francisco, and LUCIEN W. KLINE, residing at 1339 St. Charles street, in the city of Alameda, county of Alameda, State of California, citizens of the United States, have invented a new, original, and ornamental Design for a Badge, of which the following is a specification, reference being had to the accompanying drawing, forming part thereof.

In the accompanying drawing the figure is a plan view of a badge, illustrating our new design.

We claim—

The ornamental design for a badge, as shown.

HARRY W. TUCKEY.
LUCIEN W. KLINE.
